DEVICE FOR SUPPLYING HEAVY LIQUID FUELS TO INTERNAL-COMBUSTION ENGINES

Application filed January 6, 1930, Serial No. 418,804, and in Great Britain October 18, 1928.

The present invention relates to devices for supplying heavy liquid fuels to internal combustion engines, such as naphtha and the like, as the source of motive power, of the kind in which the fuel-oil and the mixture-air are admitted into a vaporizer or atomizer which is connected to the induction-manifold of the engine and which is so varied in cross-section, for example by imparting thereto an ovoid or like shape, as to cause the mixture of oil and air drawn within the said vaporizer or atomizer to assume different velocities during the course of its passage therethrough, the aspiration of the combustible mixture being generally controlled by means of a butterfly-valve or like regulating device.

The said invention has for its object to provide a fuel-supplying device of the aforementioned character which is simple in construction and reliable in operation and by means of which the mixture of oil and air can be readily regulated as to quality and temperature and thoroughly amalgamated and dispersed to produce the most efficient combustible mixture under varying atmospheric and other conditions.

According to this invention, the fuel-oil and the mixture-air are initially and independently heated by supplying the said oil and air to the vaporizer or atomizer by way of separate pipes or tubes which are passed through the exhaust-manifold of the engine, and the respective supplies of heated oil and air are independently delivered into the said vaporizer or atomizer so that the oil is caused to collect within the lower rear or inlet portion thereof and the air is caused to impinge onto the oil-bath thus formed, the resulting mixture of oil and air being thereafter caused to follow a tortuous or deflected path during its passage through the said vaporizer or atomizer. The said invention also consists in the provision of means for regulating the quantity of the respective supplies of oil and air and the temperature of the latter and for producing the requisite amalgamation and disintegration of the combustible mixture within the vaporizer or

atomizer as hereinafter described and set forth in the claims.

A fuel-supplying device in accordance with the said invention is illustrated by way of example in the accompanying drawing in which:

Figure 1 is a partly sectional elevation of the said fuel-supplying device,

Figure 2 is a sectional elevation of the exhaust-manifold of the engine,

Figure 3 is a sectional elevation of the front portion of the said fuel-supplying device, the section being taken along the line 3-3 in Figure 1, and

Figure 4 is a plan of the front or outlet portion of the vaporizer or atomizer.

Referring to the drawing, the oil is supplied from a tank (not shown) by way of a pipe *a* which passes, as seen in Figure 2, through the exhaust-manifold *b* of the engine and which is connected at its other extremity, as shown in Figure 3, to a float-chamber *c* of ordinary type which is provided with a lower inlet passage *c*¹ controlled in the usual manner by means of a needle-valve *c*². The oil-pipe *a* is preferably so dimensioned in diameter for the particular engine that the volumetric capacity of the section of the said pipe within the exhaust-manifold corresponds substantially to the quantity of oil drawn by the cylinders of the said engine in one complete working cycle. The air is supplied from the atmosphere by way of a tube *d* which likewise passes, as seen in Figure 2, through the exhaust-manifold *b* of the engine and which is connected at its other extremity, as shown in Figure 1, to a tubular chamber *e*¹ secured to the rear or inlet endportion of the body of the vaporizer or atomizer *e* and adapted to form an extension thereof. The air-tube *d*, which is also dimensioned in diameter according to the requirements of the particular engine, comprises a cut-away portion as to some convenient part of its surface and is provided thereat with a covering member *d*¹ the outer face whereof is formed with quadrant-slots or openings *d*² which are adapted to communicate with the atmosphere and which are controlled by

a corresponding upper movable quadrant-plate d^3 , so that atmospheric air can be admitted into the air-tube d in the requisite quantity for regulating or reducing the temperature of the supply of air should the air be at any time unduly heated in the exhaust-manifold b . It will be found that satisfactory results will normally be obtained by utilizing a supply of oil heated to a temperature of 40 to 50 degrees centigrade and a supply of air heated to a temperature of 65 to 70 degrees centigrade.

Thus, the oil supplied to the vaporizer or atomizer can be normally heated to the requisite temperature without any serious risk of raising the temperature of the oil to a degree liable to cause the formation of gas-locks in the supply-pipe and to impede the flow of the oil therethrough, and the supply of air passing to the vaporizer or atomizer can also be normally heated without any danger of over-heating and readily regulated as to temperature to bring the combustible mixture to the appropriate temperature adapted to produce perfect combustion under the particular conditions. A non-return valve may, however, be provided in the section of the oil-pipe between the supply-tank and the exhaust-manifold in order to prevent any gases which might be produced by an abnormal over-heating of the oil from overcoming the flow of cold oil to the said exhaust-manifold and causing the engine to stop through lack of fuel.

The heated air, regulated as to temperature as aforesaid, is delivered into the vaporizer or atomizer e in the requisite quantity by means of a butterfly-valve f of the usual type which is located in the rear or inlet portion of the tubular chamber e^1 communicating with the said vaporizer or atomizer and which is controlled by the hereinafter described operating mechanism. In order, however, to obtain a greater degree of flexibility or nicety in the regulation or control of the quality of the mixture to suit all particular conditions or requirements, an auxiliary air-tube or by-pass g is provided as shown by means of which extra air can be diverted from the air supply-tube d into the front or outlet portion of the tubular chamber or extension e^1 past the butterfly-valve f , said auxiliary air-tube or by-pass being furnished with an internal butterfly-valve or like device g^1 whereby the quantity of extra air added to the main air-supply delivered into the vaporizer or atomizer can be regulated at will. The auxiliary air-tube or by-pass g may alternatively be so extended in length that the requisite quantity of extra air as aforesaid is diverted direct into a suitable portion of the vaporizer or atomizer e .

The fuel-oil, admitted into the float-chamber c to the required level as aforesaid, flows

therefrom by gravity by way of a pipe a^1 which is connected at its other extremity (Figure 1) to the body of a needle-valve h mounted on the front or outlet portion of the tubular chamber e^1 communicating with the vaporizer or atomizer e , the said needle-valve being adapted to control an outlet passage h^1 extending partly across the said tubular chamber in front of the butterfly-valve f . The needle-valve h and the butterfly-valve f are connected together and controlled simultaneously by means of the abovesaid operating mechanism, which comprises a slightly curved longitudinal link k^1 which is attached to the stem of the said needle-valve and a T shaped pivotal link k^2 on which the said butterfly-valve is mounted, the links k^1 and k^2 being adjustably connected together at their other extremities by an intermediate transverse link k^3 . For this purpose, the longitudinal link k^1 and the intermediate link k^3 are provided at their jointed extremities as shown with a co-acting pin and hole adjustment and the pivotal link k^2 is slotted as shown as to its outer cross-portion, so that the said intermediate link can be set in various positions relatively to the said longitudinal and pivotal links. The said mechanism also comprises another transverse link k^4 which is attached to the tubular chamber or extension e^1 and connected at its other extremity to the longitudinal link k^1 , the said links being likewise provided at their junction as shown with a co-acting pin and hole adjustment. The intermediate link k^3 is further furnished with a screw-controlled adjustment k adapted to operate simultaneously the butterfly-valve f and the needle-valve h , the whole arrangement of the above-described mechanism being such that, when the said butterfly-valve is opened to the extent adapted to admit the requisite quantity of air into the vaporizer or atomizer e , the said needle-valve is automatically opened to the extent adapted to admit the requisite quantity of oil into the outlet passage h^1 extending as aforesaid across the tubular chamber e^1 communicating with the said vaporizer or atomizer.

The heated oil, regulated as to quantity as aforesaid, is delivered into the vaporizer or atomizer e by means of an internal closed pipe a^2 which is connected near the inner extremity thereof to the end of the outlet passage h^1 within the tubular chamber or extension e^1 and which is curved as shown within the lower rear or inlet portion of the said vaporizer or atomizer, the lower surface of the said pipe being bored or perforated near the outer extremity thereof as indicated at a^3 to permit of the admission of the oil into the vaporizer or atomizer. The lower wall of the vaporizer or atomizer e is formed with a substantially central and inwardly curved internal partition e^2 which extends in front 130

of and above the outer portion of the pipe a^2 and which is adapted to retain the supply of oil delivered by the said pipe so as to form within the lower rear or inlet portion of the said vaporizer or atomizer an oil-bath which is thus protected or shielded from the suction of the cylinders of the engine.

The vaporizer or atomizer e is provided as to the upper rear or inlet portion thereof with an internal deflecting baffle m which is so disposed and shaped as to cause the supply of air drawn past the butterfly-valve f by the suction of the cylinders of the engine to impinge onto and mix with the oil-bath formed as abovesaid in the lower rear or inlet portion of the said vaporizer or atomizer. The vaporizer or atomizer e is further provided as to the front or outlet portion thereof with an upper internal baffle m^1 and a lower internal baffle m^2 which are so dimensioned and arranged, relatively to each other and to the lower central partition e^2 of the said vaporizer or atomizer, that the mixture of oil and air drawn by the induction of the engine is forced to follow a tortuous or serpentine path within the vaporizer or atomizer and is thus prevented from passing out too rapidly therefrom. Also, as the combustible mixture is caused to impinge on the series of abutting deflecting surfaces constituted by the upper and lower walls of the vaporizer or atomizer e and the upper and lower internal baffles m^1 and m^2 , the said mixture is thereby thoroughly amalgamated and disintegrated before it passes out of the said vaporizer or atomizer into the cylinders of the engine.

The body of the vaporizer or atomizer e , as best seen in Figure 4, is formed as to the front or outlet portion thereof with a double-flange n containing internal passages n^1 and n^2 by means of which the said vaporizer or atomizer is connected on one side to the induction-manifold of the engine and on the other side to the ordinary petrol-carburetter which is usually brought into use for starting and warming the said engine before the heavy oil mixture is supplied thereto.

The vaporizer or atomizer may be provided as to the front or outlet portion thereof with a heat or temperature indicating device (not shown), for example of the type as usually affixed to the radiator of a motor-car, in order to enable the temperature of the gaseous mixture passing to the cylinders to be readily ascertained and maintained at the level which produces complete combustion without undue smoke under the particular conditions. In cases where the fuel-supplying device is installed on a motor-vehicle, the heat or temperature indicator may be such as to be visible to the driver of the vehicle, and suitable controls may be provided within reach of the said driver whereby any requisite adjustments for regulating the quality

and temperature of the mixture as aforesaid may be conveniently made.

I claim:

1. A device for supplying heavy liquid fuels to internal combustion engines comprising in combination, a fuel-oil supply-pipe and a mixture-air supply-pipe which are passed through the exhaust-manifold of the engine for initially and independently heating the said oil and air, a vaporizer of substantially ovoid formation communicating at one end with the said air-supply tube and at the other end with the induction-manifold of the engine, means for regulating the temperature and the quantity of heated mixture-air drawn into the said vaporizer by the induction of the engine, means for regulating the quantity of heated fuel-oil supplied by the said pipe and for delivering the said oil into the said vaporizer, means for retaining the fuel-oil within the lower rear-portion of the said vaporizer and for impinging the mixture-air onto the oil-bath formed therein, and means for producing a thorough amalgamation of the resulting mixture of oil and air within the said vaporizer as the said mixture is drawn therethrough by the induction of the engine.

2. A device for supplying heavy liquid fuels to internal combustion engines comprising in combination, a fuel-oil supply-pipe and a mixture-air supply-pipe which are passed through the exhaust-manifold of the engine for initially and independently heating the said oil and air, said oil supply-pipe being so dimensioned in diameter that the volumetric capacity of the section thereof within the said exhaust-manifold corresponds to the quantity of oil drawn by the cylinders of the engine in one complete working cycle, a vaporizer of substantially ovoid formation communicating at one end with the said air-supply tube and at the other end with the induction-manifold of the engine, means for regulating the temperature and the quantity of heated mixture-air drawn into the said vaporizer by the induction of the engine, means for regulating the quantity of heated fuel-oil supplied by the said pipe and for delivering the said oil into the said vaporizer,

means for retaining the fuel-oil within the lower rear-portion of the said vaporizer and for impinging the mixture-air onto the oil-bath formed therein, and means for producing a thorough amalgamation of the resulting mixture of oil and air within the said vaporizer as the said mixture is drawn therethrough by the induction of the engine.

3. A device for supplying heavy liquid fuels to internal combustion engines comprising in combination, a fuel-oil supply-pipe and a mixture-air supply-pipe which are passed through the exhaust-manifold of the engine for initially and independently heating the said oil and air, a quadrant-regulator mount-

ed on the said air supply-tube and adapted to control the admission of atmospheric air therein, a vaporizer of substantially ovoid formation communicating at one end with the said air supply-tube and at the other end with the induction-manifold of the engine, means for regulating the quantity of heated mixture-air drawn into the said vaporizer by the induction of the engine, means for regulating the quantity of heated fuel-oil supplied by the said pipe and for delivering the said oil into the said vaporizer, means for retaining the fuel-oil within the lower rear-portion of the said vaporizer and for impinging the mixture-air onto the oil-bath formed therein, and means for producing a thorough amalgamation of the resulting mixture of oil and air within the said vaporizer as the said mixture is drawn therethrough by the induction of the engine.

4. A device for supplying heavy liquid fuels to internal combustion engines comprising in combination, a fuel-oil supply-pipe and a mixture-air supply-pipe which are passed through the exhaust-manifold of the engine for initially and independently heating the said oil and air, a vaporizer of substantially ovoid formation communicating at one end with the said air-supply tube and at the other end with the induction-manifold of the engine, a tubular chamber forming an extension of the said vaporizer attached to the inlet-end thereof and connected to the outlet-extremity of the said air-supply tube, a butterfly-valve mounted within the said tubular chamber and adapted to control the aspiration of the heated mixture-air by the induction of the engine, means for regulating the quantity of heated fuel-oil supplied by the said pipe and for delivering the said oil into the said vaporizer, means for retaining the fuel-oil within the lower rear-portion of the said vaporizer and for impinging the mixture-air onto the oil-bath formed therein, and means for producing a thorough amalgamation of the resulting mixture of oil and air within the said vaporizer as the said mixture is drawn therethrough by the induction of the engine.

5. A device for supplying heavy liquid fuels to internal combustion engines comprising in combination, a fuel-oil supply-pipe and a mixture-air supply-pipe which are passed through the exhaust-manifold of the engine for initially and independently heating the said oil and air, a vaporizer of substantially ovoid formation communicating at one end with the said air-supply tube and at the other end with the induction-manifold of the engine, means for regulating the temperature and the quantity of heated mixture-air drawn into the said vaporizer by the induction of the engine, an auxiliary air-tube connected to the said air supply-tube and adapted to divert extra air therefrom into the sup-

ply of mixture-air admitted into the said vaporizer, a butterfly-valve mounted within the said auxiliary air-tube and adapted to regulate the quantity of extra air diverted therethrough, means for regulating the quantity of heated fuel-oil supplied by the said pipe and for delivering the said oil into the said vaporizer, means for retaining the fuel-oil within the lower rear-portion of the said vaporizer and for impinging the mixture-air onto the oil-bath formed therein, and means for producing a thorough amalgamation of the resulting mixture of oil and air within the said vaporizer as the said mixture is drawn therethrough by the induction of the engine.

6. A device for supplying heavy liquid fuels to internal combustion engines comprising in combination, a fuel-oil supply-pipe and a mixture-air supply-pipe which are passed through the exhaust-manifold of the engine for initially and independently heating the said oil and air, a vaporizer of substantially ovoid formation communicating at one end with the said air-supply tube and at the other end with the induction-manifold of the engine, a quadrant-regulator mounted on the said air supply-tube and adapted to control the admission of atmospheric air therein, a tubular chamber forming an extension of the said vaporizer attached to the inlet-end thereof and connected to the outlet-extremity of the said air-supply tube, a butterfly-valve mounted within the said tubular chamber and adapted to control the aspiration of the heated mixture-air by the induction of the engine, an auxiliary air-tube connected to the said air-supply tube and adapted to divert extra air therefrom into the supply of mixture-air admitted into the said vaporizer, a butterfly-valve mounted within the said auxiliary air-tube and adapted to regulate the quantity of extra air diverted therethrough, means for regulating the quantity of heated fuel-oil supplied by the said pipe and for delivering the said oil into the said vaporizer, means for retaining the fuel-oil within the lower rear-portion of the said vaporizer and for impinging the mixture-air onto the oil-bath formed therein, and means for producing a thorough amalgamation of the resulting mixture of oil and air within the said vaporizer as the said mixture is drawn therethrough by the induction of the engine.

7. A device for supplying heavy liquid fuels to internal combustion engines comprising in combination, a fuel-oil supply-pipe and a mixture-air supply-pipe which are passed through the exhaust-manifold of the engine for initially and independently heating the said oil and air, a vaporizer of substantially ovoid formation communicating at one end with the said air-supply tube and at the other end with the induction-manifold

of the engine, means for regulating the temperature and the quantity of heated mixture-air drawn into the said vaporizer by the induction of the engine, a float-chamber in communication with the said oil supply-pipe in which the heated fuel-oil is admitted and maintained at the requisite level, means for regulating the quantity of fuel-oil supplied from the said float-chamber and for delivering the said oil into the said vaporizer, means for retaining the fuel-oil within the lower rear-portion of the said vaporizer and for impinging the mixture-air onto the oil-bath formed therein, and means for producing a thorough amalgamation of the resulting mixture of oil and air within the said vaporizer as the said mixture is drawn therethrough by the induction of the engine.

8. A device for supplying heavy liquid fuels to internal combustion engines comprising in combination, a fuel-oil supply-pipe and a mixture-air supply-pipe which are passed through the exhaust-manifold of the engine for initially and independently heating the said oil and air, a vaporizer of substantially ovoid formation communicating at one end with the said air-supply tube and at the other end with the induction-manifold of the engine, means for regulating the temperature and the quantity of heated mixture-air drawn into the said vaporizer by the induction of the engine, a slidable needle-valve mounted in a body attached to the inlet-portion of the said vaporizer and connected to the outlet-extremity of the said oil supply-pipe, an internal outlet-passage controlled by the said slidable needle-valve and extending partly across the inlet-portion of the said vaporizer, means for delivering the heated fuel-oil admitted through the said internal outlet-passage into the said vaporizer, means for retaining the fuel-oil within the lower rear-portion of the said vaporizer and for impinging the mixture-air onto the oil-bath formed therein, and means for producing a thorough amalgamation of the resulting mixture of oil and air within the said vaporizer as the said mixture is drawn therethrough by the induction of the engine.

9. A device for supplying heavy liquid fuels to internal combustion engines comprising in combination, a fuel-oil supply-pipe and a mixture-air supply-pipe which are passed through the exhaust-manifold of the engine for initially and independently heating the said oil and air, a vaporizer of substantially ovoid formation communicating at one end with the said air-supply tube and at the other end with the induction-manifold of the engine, a tubular chamber forming an extension of the said vaporizer attached to the inlet-end thereof and connected to the outlet-extremity of the said air-supply tube, a butterfly-valve mounted within the said tubular chamber and adapted to control

the aspiration of the heated mixture-air by the induction of the engine, a slidable needle-valve mounted in a body secured to the outlet-portion of the said tubular chamber and connected to the outlet-extremity of the said oil supply-pipe, an internal outlet-passage controlled by the said slidable needle-valve and extending between the inlet-end of the said vaporizer and the said controlling butterfly-valve, an adjustable link-mechanism connecting the pivot of the said butterfly-valve and the stem of the said needle-valve and adapted to actuate the said valves simultaneously to the respective extents required for supplying the proportionate quantities of mixture-air and fuel-oil to the said vaporizer, means for delivering the fuel-oil admitted through the said internal outlet-passage into the said vaporizer, means for retaining the fuel-oil within the lower rear-portion of the said vaporizer and for impinging the mixture-air onto the oil-bath formed therein, and means for producing a thorough amalgamation of the resulting mixture of oil and air within the said vaporizer as the said mixture is drawn therethrough by the induction of the engine.

10. A device for supplying heavy liquid fuels to internal combustion engines comprising in combination, a fuel-oil supply-pipe and a mixture-air supply-pipe which are passed through the exhaust-manifold of the engine for initially and independently heating the said oil and air, a vaporizer of substantially ovoid formation communicating at one end with the said air-supply tube and at the other end with the induction-manifold of the engine, means for regulating the temperature and the quantity of heated mixture-air drawn into the said vaporizer by the induction of the engine, a slidable needle-valve mounted in a body attached to the inlet-portion of the said vaporizer and connected to the outlet-extremity of the said oil supply-pipe, an internal outlet-passage controlled by the said slidable needle-valve and extending partly across the inlet-portion of the said vaporizer, an internal closed pipe communicating at one end with and extending from the said internal outlet-passage into the lower rear-portion of the said vaporizer and perforated at the other end for delivering the heated fuel-oil thereinto, means for retaining the fuel-oil within the lower rear-portion of the said vaporizer and for impinging the mixture-air onto the oil-bath formed therein, and means for producing a thorough amalgamation of the resulting mixture of oil and air within the said vaporizer as the said mixture is drawn therethrough by the induction of the engine.

11. A device for supplying heavy liquid fuels to internal combustion engines comprising in combination, a fuel-oil supply-pipe and a mixture-air supply-pipe which are passed

through the exhaust-manifold of the engine for initially and independently heating the said oil and air, a vaporizer of substantially ovoid formation communicating at one end with the said air-supply tube and at the other end with the induction-manifold of the engine, a tubular chamber forming an extension of the said vaporizer attached to the inlet-end thereof and connected to the outlet-extremity of the said air-supply tube, a butterfly-valve mounted within the said tubular chamber and adapted to control the aspiration of the heated mixture-air by the induction of the engine, a float-chamber in communication with the said oil supply-pipe in which the heated fuel-oil is admitted and maintained at the requisite level, a slideable needle-valve mounted in a body secured to the outlet-portion of the said tubular chamber and connected to the outlet-extremity of the said oil supply-pipe, an internal outlet-passage controlled by the said slideable needle-valve and extending between the inlet-end of the said vaporizer and the said controlling butterfly-valve, an adjustable link-mechanism connecting the pivot of the said butterfly-valve and the stem of the said needle-valve and adapted to actuate the said valves simultaneously to the respective extents required for supplying the proportionate quantities of mixture-air and fuel-oil to the said vaporizer, an internal closed pipe communicating at one end with and extending from the said internal outlet-passage into the lower rear-portion of the said vaporizer and perforated at the other end for delivering the fuel-oil thereinto, means for retaining the fuel-oil within the lower rear-portion of the said vaporizer and for impinging the mixture-air onto the oil-bath formed therein, and means for producing a thorough amalgamation of the resulting mixture of oil and air within the said vaporizer as the said mixture is drawn therethrough by the induction of the engine.

12. A device for supplying heavy liquid fuels to internal combustion engines comprising in combination, a fuel-oil supply-pipe and a mixture-air supply-pipe which are passed through the exhaust-manifold of the engine for initially and independently heating the said oil and air, a vaporizer of substantially ovoid formation communicating at one end with the said air-supply tube and at the other end with the induction-manifold of the engine, means for regulating the temperature and the quantity of heated mixture-air drawn into the said vaporizer by the induction of the engine, means for regulating the quantity of heated fuel-oil supplied by the said pipe and for delivering the said oil into the said vaporizer, an internal curved partition projecting from the lower wall of the said vaporizer and adapted to form an oil-bath within the lower rear-portion thereof, means for impinging the mixture-air onto

the said oil-bath, and means for producing a thorough amalgamation of the resulting mixture of oil and air within the said vaporizer as the said mixture is drawn therethrough by the induction of the engine.

13. A device for supplying heavy liquid fuels to internal combustion engines comprising in combination, a fuel-oil supply-pipe and a mixture-air supply-pipe which are passed through the exhaust-manifold of the engine for initially and independently heating the said oil and air, a vaporizer of substantially ovoid formation communicating at one end with the said air-supply tube and at the other end with the induction-manifold of the engine, means for regulating the temperature and the quantity of heated mixture-air drawn into the said vaporizer by the induction of the engine, means for regulating the quantity of heated fuel-oil supplied by the said pipe and for delivering the said oil into the said vaporizer, means for retaining the fuel-oil within the lower rear-portion of the said vaporizer, an internal deflecting baffle located in the upper rear-portion of the said vaporizer and adapted to direct the mixture-air onto the oil-bath formed therein, and means for producing a thorough amalgamation of the resulting mixture of oil and air within the said vaporizer as the said mixture is drawn therethrough by the induction of the engine.

14. A device for supplying heavy liquid fuels to internal combustion engines comprising in combination, a fuel-oil supply-pipe and a mixture-air supply-pipe which are passed through the exhaust-manifold of the engine for initially and independently heating the said oil and air, a vaporizer of substantially ovoid formation communicating at one end with the said air-supply tube and at the other end with the induction-manifold of the engine, means for regulating the temperature and the quantity of heated mixture-air drawn into the said vaporizer by the induction of the engine, means for regulating the quantity of heated fuel-oil supplied by the said pipe and for delivering the said oil into the said vaporizer, means for retaining the fuel-oil within the lower rear-portion of the said vaporizer and for impinging the mixture-air onto the oil-bath formed therein, an inner internal baffle extending downwards across the upper front-portion of the said vaporizer, an outer internal baffle extending upwards across the lower front-portion of the said vaporizer, said inner and outer internal baffles being adapted to deflect the resulting mixture of oil and air through the said vaporizer and to produce a thorough amalgamation of the combustible mixture drawn therefrom by the induction of the engine.

15. A device for supplying heavy liquid fuels to internal combustion engines comprising

ing in combination, a fuel-oil supply-pipe and a mixture-air supply-pipe which are passed through the exhaust-manifold of the engine for initially and independently heating the said oil and air, a vaporizer of substantially ovoid formation communicating at one end with the said air-supply tube and at the other end with the induction-manifold of the engine, means for regulating the temperature and the quantity of heated mixture-air drawn into the said vaporizer by the induction of the engine, means for regulating the quantity of heated fuel-oil supplied by the said pipe and for delivering the said oil into the said vaporizer, an internal curved partition projecting from the lower wall of the said vaporizer and adapted to form an oil-bath within the lower rear-portion thereof, an internal deflecting baffle located in the upper rear-portion of the said vaporizer and adapted to direct the mixture-air onto the said oil-bath, an inner internal baffle extending downwards across the upper front-portion of the said vaporizer, an outer internal baffle extending upwards across the lower front-portion of the said vaporizer, said inner and outer internal baffles being adapted to deflect the resulting mixture of oil and air through the said vaporizer and to produce a thorough amalgamation of the combustible mixture drawn therefrom by the induction of the engine.

In testimony whereof I have signed my name to this specification.
